ABSTRACT OF THE DISCLOSURE

A key fob is disclosed comprising a pouch with a closure flap therefor, a key ring attached to the bottom of the pouch, and a medallion or other insignia attached to the exterior of the pouch by means of interlocking loops of material.

BACKGROUND OF THE INVENTION

This invention generally relates to key holders and key cases and particularly concerns key holders of the type having both a pouch for retaining individual keys loosely and a ring for retaining a set of keys.

It is known in the prior art to provide a pouch having a key ring or other key retainer therein so that the ring of keys may be kept in the pouch and drawn out as needed; however, no provision is made for retaining individual keys loosely separate from the ring. Further, the prior art does not show means for attaching a medallion for advertising or other decorative purposes.

Accordingly, it is an object of this invention to provide a key fob having means to retain both a closed ring of keys and individual loose keys.

It is a further object of the invention to provide such a key fob in which the loose keys are retained separately from the ring of keys so that any key desired is readily accessible without the need to sort out loose keys from the ring of keys.

It is yet a further object of the invention to provide such a key fob having means to retain a decorative medallion or the like.

These objects, as well as others which will become apparent as the description proceeds, are implemented by this invention which is characterized by a key fob comprising a pouch or pocket for loose keys having a closure flap, a loop of material at the closed end of the pouch retaining a ring of keys, and a second loop of material on the exterior surface of the pouch retaining a decorative medallion.

The invention itself will be better understood and additional features and advantages thereof will become apparent from the following detailed description of a preferred embodiment of the invention, such description to be taken in conjunction with the accompanying drawing, in which:

In the drawings:

FIG. 1 depicts a front view of the invention, with the closure flap in its open or unfolded position;

FIG. 2 is a cross-sectional view of the invention taken along lines II—II of FIG. 1 and looking in the direction of the arrows; and

FIG. 3 is an enlarged section of a portion of FIG. 2, showing in greater detail the mounting means for the decorative medallion.

DESCRIPTION OF THE PREFERRED EMBODIMENT

Referring now to the drawing, a key fob is illustrated as formed from a single elongated member generally indicated at 1, of leather or other flexible material, and is divided by first and second folds 2 and 3 into first, second and third portions referred to as 4, 5, and 6, respectively, in FIGS. 1 and 2.

2

The elongated member 1 has in each of its side edges, adjacent the ends of fold 2, an arcuate cutout 7 for a purpose to be more fully described hereunder. Member 1 is folded upon itself at fold 2 so that first portion 4 overlies second portion 5; these two portions are then secured to each other along their longitudinal side edges as by stitching 8, to form a pocket 9 therebetween, which pocket is open at its end opposite first fold 2 and adjacent second fold 3.

10 In its folded form, it will be noted that the cutouts 7 form a pair of openings into the pocket 9 adjacent to fold 2. A key ring 10 of conventional design is passed through the openings and the portion of the pocket therebetween, and portions 4 and 5 are then secured to each other along 15 a transverse line spaced from fold 2, as by stitching 11, to retain the ring 10 in the passageway between fold 2 and the stitching 11.

Third portion 6 of the elongated member 1 is then folded over portions 4 and 5 at fold 3 and thereby forms 20 a closure flap for the open end of pocket 9. Cooperating securing means are provided on portions 4 and 6 to secure this flap in its closed position; mating halves 12 and 13 of a conventional snap-fastener are shown, but it is clear that any suitable securing means may be provided. The 25 end of portion 4 adjacent the open end of the pocket may be provided with a recessed or cutout contoured edge 14 for ease in inserting or removing articles from the interior of the pocket 9.

At any suitable point on the exterior of the fob, securing 30 means are provided for securing a decorative medallion or the like to the fob. As shown in the drawings, a transverse slot 15 is cut in portion 4 of the fob of suitable dimensions to receive a short strap 16 of flexible material doubled upon itself to form a loop. A decorative 35 medallion or the like 17 has a transverse opening 18 therein of generally the same dimensions as slot 15. Strap 16 is looped through opening 18 in the medallion; the free ends 19 of the strap are then passed through slot 15 in the fob and secured to the underside of portion 14, 40 as by cementing. In this manner it is seen that the medallion is free to pivot within the loop of strap 16 but is securely retained thereby.

In normal use, a set of keys would be retained on ring 45 10, and any additional loose keys, papers or the like may be retained within the interior of pocket 9. It is clear that keys may be inserted or removed from either the ring or the pouch without disturbing the remaining keys.

It is clear that the above is merely a preferred embodiment of the invention, and that numerous changes can be made without departing from the spirit of the invention. For example, cementing, stitching, and/or stapling may all be used interchangeably in the construction of the fob, or the medallion and its retaining strap may be positioned upon either of the other two portions of the fob rather than the portion illustrated and described.

What is claimed is:

1. A key fob comprising:
an elongated flexible member having first, second, and third portions separated by first and second folds, respectively; cutouts on opposed sides of said member in the region of said first fold; said first portion being foldable over said second portion and secured thereto along the longitudinal edges of said first and second portions to define a pocket open at one end thereof, said cutouts defining openings into said pocket from opposite sides thereof at the end of said pocket adjacent said first fold and opposite said open end; a ring passing through said openings and the portion of said pocket therebetween; said third portion of said member being foldable over said first and second portions to close said open end of said pocket; (and)

cooperating securing means on said first and third portions to secure said folded-over third portion to said first portion to close said open end of said pocket in the region of said second fold; and a medallion and securing means comprising a flexible strap for pivotally securing said medallion to said fob.

2. A key fob as defined in claim 1 wherein the end of said first portion adjacent the open end of said pocket has a recessed contoured edge.

3. A key fob as defined in claim 1 wherein said cooperating securing means comprise mating halves of a snap-fastener.

4. A key fob as defined in claim 1 wherein said medallion having an opening therein and said strap passing through said opening and being secured to said fob.

5. A key fob as defined in claim 4 and further comprising a transverse slot in one of said portions of said flexible member, said strap passing through said slot and being secured to said portion adjacent said slot.

6. A key fob as defined in claim 5, further comprising 20 150—40 additional securing means securing said first portion to

said second portion along a transverse line spaced from said first fold to define a passageway for said ring open at the ends thereof.

7. A key fob as defined in claim 1, further comprising additional securing means securing said first portion to said second portion along a transverse line spaced from said first fold to define a passageway for said ring open at the ends thereof.
